F. H. GIBBS.
COMPARTMENT RAILWAY CAR.
APPLICATION FILED JAN. 8, 1916.

Patented Aug. 1, 1916.

2 SHEETS—SHEET 2.

UNITED STATES PATENT OFFICE.

FREDERICK H. GIBBS, OF NEW YORK, N. Y.

COMPARTMENT RAILWAY-CAR.

1,193,256.

Specification of Letters Patent. Patented Aug. 1, 1916.

Application filed January 8, 1916. Serial No. 71,048.

To all whom it may concern:

Be it known that I, FREDERICK H. GIBBS, residing at New York city, New York, and being a citizen of the United States, have invented certain new and useful Improvements in Compartment Railway-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a partial central vertical sectional view of a car body equipped with the invention it being understood that parts shown are to be duplicated at the opposite end of the car. Fig. 2 is a transverse sectional view, the section being taken on line 2—2 of Fig. 1, looking in the direction indicated by the arrow. Fig. 3 is a diagrammatical view showing general arrangement of parts. Figs. 4 and 5 are respectively side elevational and sectional views of the trackway hereinafter referred to. Fig. 6 illustrates a modification showing the simplest form of practising the invention. Fig. 7 illustrates a longitudinal sectional view the section being taken through the roof of the car as on line 7—7 of Fig. 8. Fig. 8 is a transverse sectional view the section being taken on line 8—8 of Fig. 7.

The object of the invention is to provide an improved car body adapted to be employed in transporting a plurality of kinds of materials separated by one or more bulkheads which divide the interior of the car body into a plurality of compartments.

Another object is to provide simple means for merging said compartments into a lesser number and to close an opening in the car roof, and to provide with the foregoing a modified type of roof framing and trackway combined which is designed to carry a portable hoist adapted to actuate said bulkheads.

Referring to the parts, 4 represents generally the roof of a railway car provided with a roof opening 5 for the insertion of such commodities as it may be desirable to load through said opening into the end com-

partment 6, said opening being provided with the hatch cover 7, commonly incident to railway cars.

Suspended by brackets 8, attached to the side walls 9 of the car is a bulkhead 10 which extends transversely of the car and divides the interior thereof into a plurality of compartments, as 6 and 6^a. The lower end of the bulkhead 10, as is common in this type of construction, extends to or nearly to the floor of the car and is locked in position if desired.

Near the upper portion of the interior of the car and extending at each side of the roof opening 5 at both sides of the interior, are channel-shaped trackways 20, on which slide closures 21 adapted to register with the roof opening and close the same when the bulkhead 10 is lifted to position near the roof of the car, as shown in dot and dash lines in Fig. 1. The closure 21 may comprise a carriage of any suitable construction, either with or without perforations, the object being to automatically close the opening in the roof when the bulkhead is lifted to the dot and dash position. Details of construction of the closure 21 are unimportant for the present invention. It will be noted, however, that said closure comprises a wood framing 22 extending entirely across the interior of the car, and provided at its sides next the side wall 9 with the flanged wheels 23, which are adapted to travel on the lower outstanding flanges of said channels 20, the upper flanges of said channels 20 serving as guards to prevent lifting of said closure or carriage from off its trackway.

Connected at their lower ends with said bulkhead 10 and at their upper ends with drums 15, are cables 16, which are adapted to be wound upon said drums to lift the bulkhead to a position near the roof of the car, as indicated.

Connected with the upper end of the bulkhead 10 are castings 51 at each side of the bulkhead, which castings preferably carry trunnions adapted to be seated in open-mouthed pockets in the brackets 8 and as the castings 51 are connected by bolts or equivalent means 52 with the upper ends of the bulkheads 10, said bulkheads are thereby supported when lowered to a vertical position.

Extending at an angular relation with the bulkhead 10 are lugs 54, with which are

pivotedly connected links 55, which links in turn are connected with the short legs 56 of bell-crank-levers A pivoted at 57 in brackets 58, which are secured to the inner faces of 5 said walls 9. The longer legs 59 of said bell-crank-levers are connected by means of links 60 with depending brackets 61 carried by the closures or carriages 21, and the parts are so arranged and proportioned that 10 when the bulkhead is lifted from its vertical position to a relatively horizontal position, the lugs 54 will be carried to the position shown in dotted lines in Fig. 1, and thereby, through the link 55 will throw the bell- 15 crank-lever to the position shown in dotted lines in said figure, and said bell-crank will, through the link 60, push said carriage or closure to position so that it will register with said roof opening 5. The flanged 20 wheels support said closure while it is traveling on the lower flange of the channel 20 and is supported thereby. Thus, lifting the bulkhead from its vertical to horizontal position, during which time it will swing on the 25 trunnions indicated, automatically closes the roof opening to prevent surreptitious entrance to the interior of the car, and when the bulkhead is again lowered to vertical position the closure 21 will be automatically 30 retracted to the position shown in full lines in said Fig. 1, thereby leaving said roof opening closed only by the hatch cover 7, as indicated, which hatch cover may be readily removed for the insertion of lading or suitable material into the end compartment 6.

For some reasons, the slidable carriage to close the roof opening is preferred though it may be desirable to employ the construction illustrated in Fig. 6 in which a bulkhead 10 is connected to a pivotally mounted closure 21^a by means of the link 55^a having an offset bend 60^a to accommodate the trunnions on which swing the bulkheads. Links 55^a are pivotally connected with the bulkhead and closure as indicated in Fig. 6 and when the bulkhead is lifted to the dotted, horizontal position the link 55^a swings the closure 21^a into register with the roof opening 5. In some instances it may be desirable 45 to employ a portable hoist to lift one bulkhead at a time in which case a trackway as 40 or 40^a may be employed for that purpose.

Both trackways coöperate with the carlines 41 in forming the roof structure, the trackway 40^a connecting said carlines as shown in Fig. 1, and being secured thereto, or as shown in Fig. 8 the trackway 40 forms the tension member of a roof truss frame in which 42 is the ridge or compression member 50 and 41 the carlines or struts.

What I claim is:

1. In a railway car, a roof having an opening therein, a compartment accessible through said opening, a bulkhead adapted to 65 occupy a vertical position and adapted to

swing upwardly toward said roof, and means for swinging said bulkhead toward said roof, in combination with a link pivotally connected with said bulkhead and a closure for said opening connected with said 70 link and adapted to register with said opening when the bulkhead swings upwardly toward said roof.

2. In a railway car, a roof having an opening therein, a compartment accessible 75 through said opening, a bulkhead adapted to occupy a position extending transversely of said car and adapted to swing upwardly toward said roof, a cable connected with said bulkhead and means for winding said 80 cable for swinging said bulkhead toward said roof, in combination with a link pivotally connected with said bulkhead and a closure for said opening pivotally connected with said link and adapted to register with 85 said opening when the bulkhead swings upwardly toward said roof.

3. In a railway car, a roof having an opening therein, a compartment accessible 90 through said opening, a bulkhead adapted to occupy a vertical position to divide said car into a plurality of compartments and adapted to swing upwardly toward said roof, to thereby merge said compartments, in combination with a closure for said opening, a link 95 having an offset portion intermediate the bulkhead and said closure the link being actuated by the bulkhead and adapted to automatically cause the closure to register with said opening when the bulkhead is lifted. 100

4. In a car, a combination comprising a roof with an opening therein, a pivoted bulkhead adapted to separate the interior of the car into a plurality of compartments, a separate closure for said opening, and means 105 comprising a link connected with and operable by said bulkhead adapted to cause said closure to automatically register with said roof opening when the bulkhead is lifted to a position near said roof, said link having 110 an offset portion adapted to clear the pivot of the bulkhead.

5. In a railway car, a roof having an opening therein, a compartment accessible 115 through said opening, a bulkhead extending transversely of said car thereby dividing the car into a plurality of compartments and adapted to swing upwardly toward said roof, in combination with a pivoted closure for said opening and means comprising a 120 link pivotally connected with and connecting said closure and the bulkhead and being adapted to be actuated by said bulkhead to cause said closure to register with said opening. 125

6. In combination, side and end walls, a roof having an opening, a bulkhead extending between the side walls, a closure for the roof opening and rigid means pivotally connecting the bulkhead and closure in such 130

manner that lifting the bulkhead to a position near the roof will automatically cause the closure to register with said roof opening.

7. In combination, side walls, end walls, a roof having an opening and roof framing members, a trackway connected with some of said framing members and adapted to support a lifting means, a bulkhead extending between said side walls, a closure for said roof opening, and pivoted means connecting the bulkhead and closure.

8. In combination in a railway car, side and end walls, a transversely disposed bulkhead intermediate the side walls, roof framing members, a trackway connected with said members, and means movable on said trackway independently of said bulkhead adapted to lift said bulkhead.

9. In combination in a car body, a liftable bulkhead, a roof including a trackway and means movable on said trackway independ-

ently of said bulkhead adapted to lift said bulkhead.

10. In combination in a car body, a roof having a trackway connected therewith, a lifting means movable on said trackway, and a plurality of bulkheads either of which can be connected with said lifting means to lift it toward said roof.

11. In combination, a trussed roof and trackway, a plurality of bulkheads, lifting means movable on said trackway independently of said bulkheads, and means adapted to connect either bulkhead and said lifting means.

In witness whereof I have hereunto set my hand in the presence of two witnesses.

FREDERICK H. GIBBS.
